CLAIM

The ornamental design for a storage container for batteries, as shown and described.

DESCRIPTION

The container is for storing batteries, typically dry cell batteries, in one convenient, attractive and organized location. The container can be stored within a drawer or mounted on a wall or pegboard, for example.

FIG. 1 is a perspective view of a storage container for batteries showing our new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof; and,

FIG. 7 is a bottom plan view thereof.
